United States Patent

Des. 242,441
Patented Nov. 23, 1976

242,441

TRICYCLE BODY

Joseph J. Nagle, Ten Rod Road,
Rochester, N.H. 02867

Filed Oct. 24, 1975, Ser. No. 625,499

Term of patent 14 years

Int. Cl. D12—11

U.S. Cl. D12—112

FIG. 1

FIG. 2

FIG. 1 is a perspective view of a tricycle body showing my new design; and

FIG. 2 is a side elevational view of FIG. 1 the opposite side being a mirror image thereof.

The rear of the tricycle body and substantially vertical surface facing the rear seat are understood to be plain and unornamented.

I claim:

The ornamental design for a tricycle body, as shown and described.
